UNITED STATES PATENT OFFICE

MICHAEL J. KIST, OF JOHNSTOWN, PENNSYLVANIA

GAUGE ROD

Application filed May 7, 1929. Serial No. 361,058.

This invention relates to gauge rods and more particularly to track gauge rods of the type having relatively adjustable jaws or clips to engage over the flanges of track rails, and has for its object the provision of a novel construction whereby one of the clips is completely insulated from the remainder of the rod by an insulating sleeve which is retained in position by the clip and, therefore, requires no rivets, bolts or other additional securing means.

In the drawings:

Figure 1 is an elevation showing the gauge rod of this invention positioned on the rails of a track.

Figure 2 is a plan view of the gauge rod.

Figure 3 is an enlarged detail sectional plan through the insulated end of the rod.

Figure 4 is an end view of the insulated end of the rod.

Figure 5 is an end view of the adjustable jaw end of the rod.

Figure 6 is an enlarged detail sectional elevation through the adjustable jaw.

Figure 7 is a perspective view of the locking pin.

Figure 8 is a perspective view of the nut used to retain the adjustable jaw in position.

Referring more particularly to the drawings, the numeral 2 designates the tensioning rod portion of the gauge rod which has one end upset to form diametrically opposite projecting lugs 3 comprising a head. The other end of the rod is threaded, as at 4. A pair of jaws 5 and 6 are mounted on the rod, and a nut 7 is threaded on the threaded end of the rod.

The jaws 5 and 6 have base sleeve portions 8 adapted to be slidably mounted on the rod 2 and the outer ends of the jaws are each provided with an overhanging clip portion 9 adapted to engage the upper surface of the flanges of the track rails A.

The jaw 5 has its sleeve portion bored to a greater diameter than the diameter of the rod 2 and has its outer end enlarged or flared at diametrically opposite points, as at 10, to receive the lugs 3 on the rod. The enlarged or flared portions 10 are of greater dimensions than the lugs 3 so as to provide clearance.

An insulating sleeve or bushing 12 having its one end enlarged or flared at diametrically opposite points, as at 13, to receive the upset lugs 3 on the end of the rod 2 is fitted within the bore of the sleeve portion of the jaw 5, and said jaw is forced into position at the head end of the rod so that said insulating bushing 12 and jaw 5 are forced together and over the lugs 3 thereby interlocking the jaw 5 and bushing 12 with the rod 2 so as to prevent relative rotation thereof, and providing an insulating mounting for the jaw 5.

The outer end face of the jaw 6 is flat and extends in a vertical plane when the jaw is in operative position so as to form a bearing 65 for the nut 7.

The inner face of the nut is provided with diametrically opposite grooves or slots 15 and the flat vertical outer end face of the movable jaw 6 is provided with a plurality of slots 16 of the same width as the slots 15. When the nut 7 is rotated the slots 15 are adapted to be aligned with the slots 16 to receive a locking pin or key 17.

The back walls of the slots 16 are inclined 75 inwardly adjacent the upper ends of said slots to form a deepened portion or pocket 18.

The pins or keys 17 are provided with a chamfered lower end to facilitate starting the pins, and their one side face is provided 80 with a beveled projection 19 terminating at its upper end in a square shoulder 20.

In operation, after the rod is assembled and positioned on a rail, the nut 7 will be tightened so as to force the jaw 5 and bushing 12 into tight contact with the lugs 3 forming the head on the rod, and also to force the jaw 6 into engagement with the track rail flange. When the nut 7 is tightened care is taken to position one of the slots 15 in alignment with one of the slots 16, and the pin or key 17 will be positioned in the aligned slots with the projection 19 facing the jaw 6. The pin or key will then be forced into the slots until the projection 19 enters the pocket 18 95 of the slot 16 whereby the nut will be locked against displacement.

When the rod is assembled the insulating bushing 12 will be forced within the jaw 5 so as to be protected from the elements, and 100

since the adjustments of the rod are all made with the nut 7 and jaw 6 and the jaw 5 remains stationary after it is once assembled, the insulating bushing 12 is not subjected to wear and its life is substantially indefinite.

5 I claim:

- 10 1. A gauge rod comprising a one-piece rod member having one end upset to form a head portion and the other end of said rod being threaded to receive a nut, a pair of jaws having bored base portions to receive said rod, said jaws being removably mounted on said rod, one of said jaws having its bore enlarged at its outer end to receive said upset head of said rod, and a nut threaded on the threaded end of said rod to contact with the outer end face of said other jaw to move said jaw toward the headed end of said rod to engage the flange of a track rail and secure said rod in place.
- 15 2. A gauge rod comprising a one-piece rod member having one end upset to form a head portion and the other end of said rod being threaded to receive a nut, a pair of jaws having bored base portions to receive said rod, said jaws being removably mounted on said rod, one of said jaws having its bore enlarged at its outer end to receive said upset head of said rod, an insulating sleeve mounted on said rod and having one end flared to receive said head, said sleeve being adapted to fit within and insulate said counter-bored jaw from said rod and to be held in place by said jaw, and a nut threaded on the threaded end of said rod to contact with the outer end face of said other jaw to move said jaw toward the headed end of said rod to engage the flange of a track rail and secure said rod in place.
- 20 3. A gauge rod comprising a one-piece rod member having one end upset at diametrically opposite points to form an enlarged head, and the other end of said rod being threaded to receive a nut, a pair of jaws having their base portions bored to receive said rod, said jaws being removably mounted on said rod, one of said jaws having the outer end of its bore enlarged at its top and bottom to receive said upset head of said rod and form an interlock therewith to prevent rotation of said jaw, and a nut threaded on the threaded end of said rod to contact with the outer end face of said other jaw to move said jaw toward the headed end of said rod to engage the flange of a track rail and secure said rod in place.
- 25 4. A gauge rod comprising a one-piece rod member having one end upset at diametrically opposite points to form an enlarged head, and the other end of said rod being threaded to receive a nut, a pair of jaws having their base portions bored to receive said rod, said jaws being removably mounted on said rod, one of said jaws having the outer end of its bore enlarged at its top and bottom

to receive said upset head of said rod, an insulating sleeve mounted on said rod and having one end flared outwardly at diametrically opposite points to receive said head portion of said rod, said sleeve being adapted to fit within and insulate said first named jaw from said rod, said first named jaw and said sleeve being interlocked with said head to prevent rotation of said jaw and sleeve relative to said rod, and a nut threaded on the threaded end of said rod to contact with the outer end face of said other jaw to move said jaw toward the headed end of said rod to engage the flange of a track rail and secure said rod in place.

70 75 80 In testimony whereof, I have hereunto set my hand.

85 MICHAEL J. KIST.
